US00D577687S

(12) United States Design Patent
Harris, IV et al.

(10) Patent No.: US D577,687 S
(45) Date of Patent:  Sep. 30, 2008

(54) INDICATOR FOR A FUSE

(75) Inventors: Edwin James Harris, IV, Oak Park, IL (US); Michael Schlaak, Chicago, IL (US)

(73) Assignee: Littelfuse, Inc., Des Plaines, IL (US)

() Term: 14 Years

(21) Appl. No.: 29/297,346

(22) Filed: Nov. 8, 2007

Related U.S. Application Data

(62) Division of application No. 29/250,430, filed on Nov. 14, 2006, now Pat. No. Des. 559,203.

CLAIM

The ornamental design for an indicator for a fuse, as shown and described.

DESCRIPTION

FIG. 1 is a top perspective view of an indicator for a fuse showing our new design;

FIG. 2 is a front view thereof, wherein the rear view is a mirror image thereof;

FIG. 3 is a first side view thereof;

FIG. 4 is a second side view thereof; and,

FIG. 5 is a top view thereof.

The ornamental design which is claimed is shown in solid lines in the drawings. Any broken lines in the drawings are for illustrative purposes only and form no part of the claimed design.
